 International Business Machines Corporation,
 New York, N. Y., a corporation of New York

Application October 7, 1933, Serial No. 692,580

6 Claims. (Cl. 101—93)

This invention relates to tabulating machines and more specifically to improvements in the printing mechanism of such machines.

The invention finds particular utility in connection with tabulating machines of the type such as disclosed in Patent No. 1,762,145, granted June 10, 1930 to G. F. Daly and R. E. Page. In tabulating machines of such type, the printing mechanism usually consists of a plurality of type bars mounted for vertical reciprocation and are moved upwardly and down again for each card fed through the machine. During the upward stroke the type bars are differentially positioned under control of perforations in record cards and at the end of their upward stroke an impression is taken from the variously positioned type bars. Following this, the type bars are moved downwardly to restored position. In order that the machine cycles do not become too lengthy, the restoring movement of the type bars is necessarily effected in the shortest possible time, which, however, takes an appreciable portion of a machine cycle and where the number of type bars to be restored is fairly large, the inertia 25 of the mass to be restored has a limiting effect on the rapidity with which the machine may be operated.

The principal object of the invention is to improve the organization of the printing mechanism of tabulating machines whereby the loss of time during machine cycles is minimized by eliminating the independent resetting operations and the speed of the machine may be increased as a consequence.

Each type carrier is provided with dual positioning mechanism alternately operable under control of successively analyzed records and adapted to alternate in their operations so that one positioning device may position the type carrier and then move it to restored position while the other tends to operate in reversed sequence; that is, while one device is restoring the type carrier, the other will take control thereof to move it to a new position.

Various other objects and advantages of the invention will be obvious from the following particular description of one form of mechanism embodying the invention or from an inspection of the accompanying drawings; and the invention also constitutes certain new and novel features of construction and combination of parts hereinafter set forth and claimed.

In the drawings:

Fig. 1 is an isometric view of one of the type carriers and the positioning devices therefor.

Fig. 2 is a detail showing the operating cams for the printing mechanism.

Fig. 3 is an end view of the stop pawls for locating the positioning devices.

Fig. 4 is a simplified circuit diagram showing the connections between the card analyzing devices and the controlling magnets for the printing mechanism.

Referring to Fig. 4, record cards R are fed downwardly by means of the usual picker 10 past 10 a set of analyzing brushes 11 which analyze perforations in record cards and complete circuits through printer magnets 12 at differential times depending upon the location of the perforation in the columns analyzed by the brushes. 15

Cam controlled contacts 13 and card lever contacts 14 control the completion of the circuits so that none will be established unless record cards are moving past the brushes. Feed rollers 15 serve to advance the cards past the brushes and 20 the rollers are driven by gearing generally designated at 16, operated under control of motor 17. This is the usual arrangement of the card feeding mechanism and for further description thereof, reference may be had to the patent referred to. Also driven by motor 17, through gears 18, is a shaft 19 which drives the printing mechanism in unison with the feeding of the record cards past the brushes. 25

Referring now to Fig. 1, each type carrier 20 30 is supported upon a shaft 21 by means of an arm 22 and has integral therewith a block 23 through which the movement of the type carrier is controlled. A pair of fingers 24 and 25 are adapted to cooperate with one side of block 23 to advance 35 the carrier to printing position. A pair of fingers 26 and 27 cooperate with the opposite side of block 23 and serve to move the carrier back to restored or normal position. The fingers 26 and 27 are freely pivoted on the shaft 21 and are 40 connected by means of springs 28 and 29 to the fingers 24 and 25, respectively, thus forming a pair of resilient scissors devices.

Finger 24 has integral therewith an arm 30 connected by a spring 31 to a bail 32 and finger 45 25 has a similar arm 33 connected by a spring 34 to a bail 35. Bails 32 and 35 are pivoted upon the shaft 21 and are provided with cam follower rollers 36 and 37 controlled by cams 38 and 39, respectively. 50

The arrangement is such that as bail 32 is rocked in a clockwise direction by its cam, the bail 35 will be moved in the opposite direction by its cam 39. Movement of either bail in a clockwise direction will cause the associated arms 55

38 or 33 to follow under control of springs 31 and 34 and if the movement of the arms is not obstructed, the fingers 24 and 25 will cooperate with the block 23 and carrier 20 to move the latter through the full extent of its movement.

Integral with finger 24 is an arm 40 having ratchet teeth 41 and integral with finger 25 is an arm 42 having similar ratchet teeth 43. Teeth 41 and 43 are adapted to cooperate with stop pawls 44 and 45 respectively, whenever the arms move in a clockwise direction. The pawls are pivotally mounted upon rod 46 and both are spring-pressed into engagement with a latch 47 normally held in the position shown in Fig. 2 by the armature 48 of printing magnet 12. As arm 40 moves in a clockwise direction and finger 24 and carrier 20 move likewise, energization of printer magnet 12 under control of a perforation in the record will trip pawl 44 into engagement with one of the teeth 41 and further movement of arm 40 and consequently carrier 20 will be interrupted, spring 31 yielding as bail 32 continues to its extreme position. At this time there is a momentary dwell in the movement of the parts during which the usual printing hammers 49 are tripped to take an impression from the positioned type elements.

The position of the parts in Fig. 1 represents the relationship of the parts with carrier 20 positioned to present the "2" type element in printing position, the pawl 44 having been tripped as the tooth 41 corresponding to the "2" type element moved past the stopping position. Following the printing operation, the cam 50 carried by shaft 19 will cooperate with the follower roller 51 mounted upon a link 52, one end of which is supported by an arm 53 on shaft 54 to which is also secured a bail 55 whose function is to restore the latches 47.

As the bail 32 now moves in a counterclockwise direction carrying with it the arms 30 and fingers 24, the springs 28 will tend to urge the fingers 25 and through them the carriers 20 to restored position. In the meantime, however, the ball 35 is moving in a clockwise direction and finger 25 and arm 42 are moving in the same direction and when the extremity of finger 25 strikes block 23, it will pick up carrier 20 and, overcoming the tension of the relatively light spring 28, will reverse the direction of movement of the carrier and assume control thereover. During this clockwise movement of the ball 35, the next succeeding record card is passing the brushes 11 and magnet 12 may be energized to engage one of the teeth 43 to differentially position the finger 25, thus setting the carrier 20 in a new position.

It will be observed that the movement of finger 25 may be interrupted before it has made contact with block 23, as for instance when the pawl 45 is tripped to engage the lowermost tooth 43. In this event, the carrier 20 and block 23 will advance until the latter engages the finger 25 and will be interrupted at that point, finger 24 continuing to advance to the limit of its movement alone.

Due to the overlapping operation of the two positioned devices, carrier 20 will, under certain conditions, move directly from one printing po-

sition to the next printing position and under other conditions, it may first move in a restoring direction from one printing position and its direction of movement reversed and the carrier advanced to the next printing position.

The resilient mounting of pawls 44 permits the positioning of the two arms 40 and 42 under control of a single magnet 12, the arrangement being such that as one set of teeth is being moved upwardly to restoring position during which the cooperating pawl is obviously being vibrated under control of the teeth, this vibration of the pawl will not interfere with the other pawl which can be operated independently to coact with the advancing arm.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. In a machine of the class described, means for analyzing record cards successively for perforations in the columns thereof, a type carrier associated with each column, a pair of positioning devices for said carrier and means for alternately controlling said positioning devices under control of successive cards.

2. In a machine of the class described, means for analyzing record cards successively, a type carrier and means for advancing the same, means controlled by a record card for positioning said carrier during its advance, means for restoring said carrier and further means controlled by a subsequently analyzed record card for repositioning said carrier during its movement of restoration.

3. In a machine of the class described, a type carrier, resilient means for advancing said carrier, resilient means for restoring said carrier and record controlled means for interrupting said carrier during movement in either direction.

4. In a printing machine, a type carrier, means for advancing said carrier, means controlled by a perforation in a record card for positioning said carrier during its advance, means for restoring said carrier to its initial position, and means for causing advance of said carrier to a new position before it has been restored to its initial position.

5. In a printing machine, a type carrier, means for moving said carrier in two directions, positioning means and means controlled by a record card for controlling said positioning means to limit the extent of movement of said carrier in either direction.

6. In a printing machine, a type carrier, means for advancing the same to printing position, record controlled means for interrupting the advance of said carrier at differential times, restoring means for the carrier and further record controlled means for interrupting the restoration of said carrier at differential times.

JAMES W. BRYCE.
